UNITED STATES PATENT OFFICE.

ABNER JUDSON MCGEHEE, OF JACKSON, TENNESSEE, ASSIGNOR OF ONE-HALF TO WILLIAM M. MOSS, OF SAME PLACE.

SASH-LOCK.

SPECIFICATION forming part of Letters Patent No. 671,921, dated April 9, 1901.

Application filed December 10, 1900. Serial No. 39,287. (No model.)

To all whom it may concern:

Be it known that I, ABNER JUDSON MCGEHEE, a citizen of the United States, residing at Jackson, in the county of Madison and State 5 of Tennessee, have invented certain new and useful Improvements in Sash-Locks, of which the following is a specification, reference being had therein to the accompanying drawings.

10 The object of my invention is to provide a new and effective lock which will secure both window-sashes in any desired position, preventing them from being raised or lowered from the outside and also holding them tightly 15 in the frame, so that they will not rattle.

The invention consists of the novel details of construction and arrangement of the parts, as hereinafter fully described and claimed.

Referring to the accompanying drawings, 20 which form a part of this specification, similar characters of reference indicating corresponding parts in all the views, Figure 1 is a horizontal section through the window-frame at the meeting-rails of the sash. Fig. 2 is a 25 sectional view of the complete lock and its key. Fig. 3 is a perspective view of the clamping-rod. Fig. 4 is a perspective view of the double-threaded rotating sleeve and clamp. Fig. 5 is the key adapted to engage 30 the sleeve.

Referring to the drawings, A represents the lower sash; B, the upper sash; C C', the inner and outer facings of the frame; D D', the inner and outer stop-beads; E, the parting- 35 strip, and F the window-jamb. The lock is located in a recess in the jamb of the window in such a manner that the angled end 1 of rod G rests against the outside of the top sash and the clamp I against the inner side of the 40 bottom sash, as shown in Fig. 1.

The rod G has one end extended at right angles to form the clamp I, and the other end has the right-hand threads 2. Sleeve H is fitted to rotate in the jamb of the window and 45 has the right-hand threads 3 on its inside to engage the rod G and the left-hand threads on its outside to engage the clamp I, which has left-hand threads in its aperture, and its end 5 is provided with a square or angular

aperture to engage the square or angular stem 50 6 of the key J.

The sleeve H is turned by means of the key J, and if turned to the right the rod G is drawn up into it and against the top sash by the right-hand threads 2 and 3, and the clamp 55 I is thrust against the lower sash by the left-hand threads 4, and the two sashes are thus clamped firmly against the parting-stop E and are firmly held against any effort to move them in any direction. When the sleeve is 60 turned to the left, the clamps quickly recede from the sash and allow them to move freely in the frame.

The key J has a long square or angular stem 6 fitted to the square or angular aperture 65 5 in the sleeve H, so that it will fit up close to the window-facing when not in use, and may be drawn outward, so as to be easily gripped in the hand, when it is desired to operate the lock.

This lock may be easily adjusted to any thickness of sash or frame by screwing the sleeve H on or off of the rod G and the clamp I back and forth on the sleeve.

Having thus fully described my invention, 75 I claim as new and desire to secure by Letters Patent—

A sash-lock comprising a rod angled at one end to form a clamp and threaded at the other end at such length as to enable it to be 80 screwed some distance in or out of the sleeve, in order to adjust the length of the lock to the distance from the outside of the top sash to the inside of the window-facing, a tubular sleeve having threads on its inside reverse- 85 handed from the threads on its outside, a threaded clamp mounted on said sleeve, and a key having an angular stem inserted into an angular aperture in the end of said sleeve, all substantially as and for the purposes specified.

In testimony that I claim the foregoing as my own I have hereunto affixed my signature in the presence of two witnesses.

ABNER JUDSON MCGEHEE.
